United States Patent

Des. 235,718
Patented July 8, 1975

235,718

DRESSER

Aaron Donner, Weston, Conn., assignor to
The Lane Company, Inc.

Filed July 10, 1974, Ser. No. 487,375

Term of patent 14 years

Int. Cl. D6—04

U.S. Cl. D6—154

The figure is a front, top and right side perspective view of a dresser showing my new design, the left side being substantially identical to the right.

The rear of the dresser is plain and unornamented.

I claim:

The ornamental design for a dresser, as shown and described.
